UNITED STATES PATENT OFFICE.

ALBERTO GONZÁLEZ ZÚÑIGA, OF LIMA, PERU.

COMFORT-CHAIR.

1,231,686.

Specification of Letters Patent.

Patented July 3, 1917.

Application filed May 24, 1915. Serial No. 29,986.

To all whom it may concern:

Be it known that I, ALBERTO GONZÁLEZ ZÚÑIGA, a citizen of Peru, and a resident of Lima, Peru, have invented a new and Improved Comfort-Chair, of which the following is a full, clear, and exact description.

My invention relates to comfortable chairs, and has reference more particularly to a chair which can be adjusted to any desired position by the person occupying the chair.

An object of the invention is to provide a comfortable chair having a swinging back and foot rest with means for synchronizing their swinging movement.

Another object of the invention is to provide a comfort chair the seat of which is mounted to swing, with means for arresting the swinging movement of the seat.

20 A further object of the invention is to provide a comfort chair having a swinging back and foot rest, including means for locking the foot rest at a predetermined position while leaving the back of the chair free to swing.

30 A still further object of the invention is to provide a comfort chair in which there is a swinging back and foot rest, with means for locking the swinging back at any desired point of the swinging arc of the back.

35 A still further object of the invention is to provide a comfort chair having a swinging back and foot rest which are foldable on the seat, and which back, seat and foot rest are collapsible longitudinally.

40 Another object of the invention is to provide a collapsible support from which a comfort chair may be suspended to swing, with means carried by the support to lock the swinging movement of the chair in the support.

45 With the above and other objects in view, the nature of which will more fully appear as the description proceeds, the invention consists in the novel construction, combination and arrangement of parts as herein fully described, illustrated and claimed. In the accompanying drawings, forming 50 part of the application, similar characters of reference indicate corresponding parts in all the views.

Figure 1 is a perspective view of my chair

showing it locked to prevent the swinging movement thereof in the support;

55 Fig. 2 is a similar view showing the back and foot rest locked to the seat;

Fig. 3 is a front elevation of the chair with the flexible covering thereof removed showing the chair free to swing in the support;

60 Fig. 4 is an enlarged partial sectional view through the support on line 4-4, Fig. 1, showing the chair proper in front elevation;

65 Fig. 5 is an enlarged side elevation of the motion transmission means connecting the back to the foot rest;

Fig. 6 is a section on line 6-6, Fig. 5;

Fig. 7 is a section on line 7-7, Fig. 6; 70

Fig. 8 is a section on line 8-8, Fig. 5;

Fig. 9 is an enlarged side elevation of the lower end of the foot rest;

Fig. 10 is an enlarged front elevation of the upper end of the back;

75 Fig. 11 is a section on line 11-11, Fig. 10;

Fig. 12 is a section through one of the upper ends of the chair support on line 12-12, Fig. 2;

80 Fig. 13 is a plan view of the longitudinal bars 15 with the transverse member thereof collapsed and the flexible member removed to show the relative position of the connections.

Fig. 14 is an enlarged fractional side elevation of the lower portion of the upright of the support; and

85 Fig. 15 is a perspective view illustrating the connection of the upper end of the triangular suspension frame for the chair.

90 Referring to the drawings, the seat of the chair comprises two longitudinal bars 15 properly spaced by transverse members 16 connected to the longitudinal bars adjacent the ends thereof and depressed below 95 said longitudinal bars so that a flexible member 17 tied to the rods 18 will not, when weight is applied thereto, engage said transverse members 16. Each of the rods 18 is connected to a corresponding bar 15 100 and spaced therefrom to facilitate the tying of the flexible member 17 to the bars. A link 19 is pivotally attached between its ends to the front end of each of the bars 15. The link is preferably located between the 105 bar and the corresponding rod. One end of

a link 20 is mounted on each pivot of the link 19. Each of the links 20 is preferably located between the link 19 and the corresponding rod 15. A link 21 is pivotally connected to the rear end of each bar 15.

- 10 The upper end of each link 21 is connected by a pivot 24 to a corresponding longitudinal bar 22 adjacent the lower end thereof. The lower end of each bar is cut on the bias and normally engages a pin 23 provided on each link 21. This bias is cut so that a movement of the bars from the longitudinal bars 15 will cause the link 21 to move with the bars 22. A reverse movement 15 of the bars will permit the said bars 22 to swing on the pivots 24 which connect them to the links 21. The purpose of this will appear hereinafter. The upper ends of the longitudinal bars 22 are properly spaced 20 by a transverse member 25. Each of the bars 22 is provided with a rod 26 suitably spaced from the bar so as to facilitate the tying of the flexible member 17 to said bars.
- 25 The transverse member 25 comprises two pivotally connected sections 66, each connected pivotally to the adjacent end of the bar 22 by an end portion 65 which is locked to a projection 27 on the bar by a 30 slide 28, also on the bar, and actuated by a spring 29. The joint of the sections 66 has a stop 67 limiting the movement of the sections to alinement under the tension of the flexible member 17 engaged by the section 35 66. To move the sections it is necessary to unlock the end portions 65 from the bars 22 and swing said portions from the bars.

- 40 A bar 30 connects pivotally each bar 22, above its pivot 24, and the other end of the link 20 which is on the same side of the chair seat. A lateral projection 31 is provided on each of the links 19 adjacent the upper ends thereof to be engaged by the links 20 when the back of the chair is swung 45 downwardly, that is, away from the seat. Pivotally connected to the lower end of each link 19 is a longitudinal bar 32. The said lower end of each link 19 is cut on the bias and is adapted to engage a similar biased 50 edge of a projection 33 secured to the bar 32, whereby the bar 32 is maintained in alinement with the link 19 when the bias edges are in contact. These bias edges are so related that when the links 19 are moved 55 on their pivots by the links 20 the longitudinal bars are caused to move therewith, or that, when the longitudinal bars are moved downwardly, the links 20 are caused to move with the links 19. It will be noted 60 that the bias permits a free upward movement of the bars 32 without the links 19 participating in the said movement.

65 The portion of the flexible member 17 which extends from the seat between the longitudinal bars 32 is secured to rods 34,

similar to rods 18 and 26, and similarly spaced from the corresponding bars 32. The lower ends of the longitudinal bars 32 are properly spaced by a transverse member 35 pivotally connected to each of the 70 bars adjacent the lower end so as to swing outwardly. Said transverse member 35 is constructed similarly to the transverse member 25 and engages the lower end of the flexible member 17 and stretches longitudinally the portion of the flexible member extending between the bars 32 when said transverse member is brought into a plane with said longitudinal members. It is maintained in the plane with the longitudinal 80 members by a locking device forming part of a foot bar or support 36. The foot bar is constructed similarly to the member 25 and is connected pivotally to the lower ends of the bars 32. The ends of the foot bar 85 at the pivots are provided with a notch 37 adapted to engage a pin 38 on the transverse member 35 when said foot bar is at right angles to the foot rest, which is formed by the foot bar, the longitudinal bars 32, 90 the transverse member 35, and the flexible member stretched therebetween.

The connection of the seat back with the foot rest by means of the bars 30 and links 20 causes the foot rest to swing upwardly 95 when the back is swung downwardly. The downward swinging of the foot rest will cause an upward swinging movement of the back. The back can be locked to the seat at any desired position by a locking mechanism provided on each side of the seat. The locking mechanism comprises an arcuate member 39, preferably semi-circular, the ends of which are secured to the corresponding longitudinal bars 22. The center of curvature of said member 39 is in the axis of the pivot 40 which connects the bar 22 with the bar 30. The arcuate member 39 passes between the bar 30 and a jaw 41 secured to the bar 30, so as to be free to move to and from the said bar. A lever 42 is secured to the bar 30, the fulcrumed end 43 of which bar is concave to engage the convex side of the jaw 41, so that when the lever 43 is moved into the position shown in Fig. 5, the 110 jaw 41 clamps the arcuate member 39 to the bar 30 and prevents the back from swinging relative to the seat. It also locks the foot rest in its downward movement; although the foot rest is free to move outwardly, as 115 can be easily seen from Fig. 5. When the end 43 of the lever is in alinement with the jaw, the back is free to swing.

The foot rest may be locked to the seat when it is brought to a level therewith. 120 The locking means is disposed on each side of the seat and consists of a slide 44 secured on the inner side of each bar 15. A spring 45 is associated with each slide 44 and normally maintains one end of the slide in the 130

path of the upper end of the corresponding link 19, so that when said links 19 are brought into alignment with the bars 15 they displace the corresponding slides to snap 5 thereunder, whereby the foot rest is locked to the seat when the same is in plane therewith, as indicated in Fig. 2. To unlock the foot rest from the seat and maintain the slides 44 clear of the upper ends of the links 10 19, each slide 44 is connected to a pivotal arm 46 by a link 47. The link 47 is pivotally connected to the arm 46 at a point above the pivotal connection of the arm with the bar 15, so that the two pivots will be on a 15 straight line, as shown in Fig. 5, when the slide 44 is moved to clear the upper end of the corresponding link 19. To maintain the arms 46 against the bars 15 when the slides 44 are in operative position, the links 47 engage 20 the slides 44 by means of elongated slots 48, so that they have an initial displacement relative to the slides and thus permit the arm to be folded against the bar 15, as shown in Fig. 2.

25 To render the chair still more comfortable, suspension members 49 are provided therefor. One of the suspension members 49 is connected to the bar 30 adjacent the rear end thereof, and the other adjacent the front 30 end of the bar. The two suspension members are in pivotal connection with their other ends. The pivotally engaged ends of the suspension members 49 are made to engage a notch 50 on an arm 51 extending laterally from up-rights 52 of the chair support. By the provision of this suspension means the chair is free to swing in the chair support; that is to say, a person occupying 35 the chair can swing therewith.

40 To lock the seat of the chair, and therefore stop the swinging movement of the chair, a pawl 53 is provided in each of the uprights 52. Each of the bars 30 carries a depressible member 54 having a notch 55 adapted to be 45 engaged by the corresponding pawl 53. Compensating levers 56 are provided for each pawl 53 to lock said pawl in operative or in inoperative position, as shown in Figs. 1, 3 and 4. The levers comprise a slotted 50 link 56^a pivoted to the up-right 52 with one end and engaging with a pin at the other end the slotted end of a link 56^b pivoted between the ends on the upright. The other end of the link 56^b is connected by a link 56^c 55 to the pawl 53. A handle 56^d pivoted at one end to the upright 52 has a pin adjacent the pivoted end engaging the slot of the link 56^a. The reason for making the member 54 depressible is to bring said member into engagement with the pawl after the said pawl 60 has been locked in operative position by means of the compensating levers.

It will be noted that the suspension members 49 and the bars 30 form the suspension frame for the seat, from which the said

seat is suspended and with relation to which frame the seat is movable. The suspension frame, as stated, can be locked by means of the compensating levers 56. This prevents the swinging movement of the frame, but 70 the seat suspended from the frame is movable relative thereto whether the frame is locked or free to swing when the back is swung. Due to this arrangement, a person occupying the chair and applying pressure 75 to the back cannot fall, as the downward movement of the back forces the seat to rise; therefore the pressure of the person applied to the back reacts against its own weight. Relief of pressure from the back and application of pressure to the foot rest helps the 80 back to swing to a substantially vertical position.

As seen from the drawings, the seat, with its swinging back and foot rest, is suspended 85 from the support, and, therefore, can be easily hooked off therefrom. The members 49 are separable on their common pivot and, therefore, foldable against the corresponding bar 30. To properly fold the member, 90 the rear member 49 has a link 49' connecting it to the bar, whereby said rear member will fold on to the front member 49. In addition to the foldability of the foot rest on the seat and the back over the foot rest, the 95 back, seat and foot rest are collapsible longitudinally by making the transverse members thereof collapsible; that is to say, the members 16, 25, and 35 and foot bar 36 are foldable.

100 The transverse members 16 of the seat comprise depending portions 57 rigidly secured to the bars 15. Pivotally connected to the depending portions 57 are end portions 58 to each of which is pivotally connected a 105 bar portion 59. The end portion 58 and the bar portion 59 have biased ends 60 adapted to engage when the bar portions 59 and the end portions 60 are substantially in alignment, as shown in Fig. 8. The bar portions 60 are 110 pivotally connected to each other at 61. One of the bar portions is provided with an extension 62 to which one end of an arcuate segment 63 is pivotally attached. The other end of the segment is pivotally attached to a 115 lever 64 between its ends, one end of the lever being pivotally attached to the other bar portion 59. When the non-pivoted end of the lever 64 is brought into alignment with the bar 16, the biased ends of the bar portions 59 are moved into engagement with the corresponding biased ends of the end portions 58; and the end pivot of the lever 64 is below a straight line connecting the pivots of the arcuate member 63 and, therefore, it is below the dead center and locked. To collapse the bar 16 it is necessary to move the lever 64 in the direction indicated by the arrow in Fig. 8. The pivotal connections of the end portions 58 with the depending por- 125

130

tions 57 permits the swinging of the transverse member 16 into a plane parallel with the longitudinal bars 15 when the transverse member is collapsed and draws the longitudinal bars 15 together. See Fig. 13.

The chair support is also made collapsible, to render the transportation thereof easier. Each upright has a central standard formed of two members 68 and 69 pivoted below the [10] upper brace which is formed of two members 70 each pivoted to the member 68 to swing in the same plane. The lower brace of the upright is formed of two members 71, each pivoted to the link 76 which is in turn [15] pivoted to the standard portion 69. Connected pivotally to each of the members 71 is a side member 72, each of which is, in turn, pivotally connected to one of the brace members 70. It will be noted that the pivotal joints of the members 71 and 72 are in a plane at right angles to the pivotal joints of the members 68 and 69. Side members 73 connect a socket 74, provided at the upper end of the portion 68 of the central standard, with the braces 70 to which the members 73 are pivotally connected and whereby the side members 73 and the portion 68 can be folded over the lower part of the upright of the support.

[30] The two uprights of the support are interconnected at the bottom by the members 75 which are pivotally connected to each other and to the standard portions 69 above their links 76. The two members 75 are further [35] connected by a jointed bar 77 having a locking link member 78 for retaining the jointed bar straight between the members 75 to prevent the movement of the uprights toward each other. The locking member 78 permits the bar 77 to collapse only when it is forced toward the members 75 and whereby the uprights are drawn toward each other.

The standard portion 68 has an extension 79 at the joint with the portion 69. This extension has a curved link 79' which is pivotally connected by a link 80 to the adjacent member 75. A spring-actuated pawl 81 is attached to each projection 79 to engage a pin 82 provided on the corresponding portion 69 of the central standard. This pawl normally locks the member 68 to the member 69. By disengaging the pawl 81 from the pin 82, the upper part of the upright can be folded toward the lower part of the [50] standard. The folding movement of the upper part draws the members 71 of the lower brace inwardly, and, consequently, brings the two side members 72 toward each other. When the upper part of the upright [55] is collapsed against the lower part, the two side members 72 are substantially parallel. After the two sides of the uprights are so collapsed, by collapsing the central part 78, the two collapsing uprights can be brought [60] close together, thus greatly diminishing the

space occupied by the support, which is very important for the transportation of the chair.

The side members 72 are preferably provided with casters 83 to facilitate the rolling of the chair when the same is mounted. The arms 51 are also foldable in alinement with the uprights 52 as indicated in Fig. 12. The sockets 74 of the uprights are adapted to receive detachable stems 85. To one of [70] the stems 85 a book support 84 is secured by means of a spring clamp 86 which extends from the book support to the stem. By compressing the ends of the clamp 86, the same can be moved on the stem so as to [75] adjust the support. The book support 84 swings in a horizontal plane on the clamp support 86; and it also swings in a vertical plane on a brace which connects it to the clamp, so that various adjustments of the [80] book support may be obtained. Springs 87 are provided for clamping a book or any other reading matter to the support 84. The other stem 85, a portion only of which is shown, is intended for a table, which can be [85] similarly adjusted on the stem by means of a similar clamp. This was omitted as the structure is substantially similar to what has been stated in reference to the book support.

From the above description it will be seen that in my chair a person occupying the same can easily control any desired position of the swinging back thereof and that the chair can be transformed into a lounge. [95] There is no danger that a person occupying the chair will fall due to sudden application of pressure to the back of the chair, in view of the fact that the motion-transmission means which connects the back with the foot rest and the seat causes the seat to move upwardly while the back moves downwardly, therefore reacting against the weight of the person occupying the chair. The collapsibility of the chair and the support thereof [100] renders the same more easily transportable and, therefore, more convenient.

The single flexible member 17 which engages the rods connected to the bars of the seat, back and foot rest, engages the transverse members only at the ends thereof; therefore no part of a person occupying the chair can come in contact with the transverse bars of the chair and thereby be rendered uncomfortable. The collapsible transverse members 16, 25 and 35 maintain the flexible member 17 on the seat, back, and foot rest of the chair when the same is in operative position, in cases where the chair is collapsible. The tautness of the flexible [115] member 17 does not interfere with the foldability of the foot rest and back over the seat; but the tautness is destroyed when the seat, back, and foot rest are collapsed longitudinally, as described.

While I have described the principle of operation, together with the device which I now consider to be the best embodiment thereof, I desire to have it understood that 5 the chair shown is merely illustrative and that such changes may be made as are within the scope of the appended claims.

I claim:

1. In a comfort chair, a seat, a swinging back and a swinging foot rest associated with the seat and adapted to be folded over the seat, motion-transmission means connecting the back to the foot rest and seat, and means for collapsing longitudinally said foot rest, back and seat.
2. In a comfort chair, a support, a seat suspended from the support and detachable therefrom, a swinging back and a swinging foot rest associated with the seat and adapted 20 to participate in the movement of the seat within the support, said foot rest and back being adapted to be folded over said seat, said seat, back, and foot rest having means whereby the same can be collapsed longitudinally, motion-transmission means connecting the back to the foot rest whereby a downward swinging movement of either is transmitted to the other, and means for locking the foot rest and back to the seat.
3. In a comfort chair, a seat, a swinging back and a swinging foot rest associated with the seat and foldable thereover, a unitary flexible member covering said seat, back and foot rest, motion-transmission means 35 connecting the back to the foot rest whereby a downward, swinging movement of either is transmitted to the other, and means for locking the back to the seat at any point of the swinging arc of said back.
4. In a comfort chair, a support, a suspension frame mounted to oscillate in the support, a seat suspended from the frame, a back pivotally connected to the frame and seat, a foot rest pivotally connected to the 45 seat and engaging the frame, said foot rest and back being foldable on to the seat, a unitary flexible member covering said back, seat and foot rest, said suspension frame being detachable from the support and foldable toward the seat, and means associated 50 with the back, seat, and foot rest whereby the same are collapsible longitudinally thereof.
5. In a comfort chair, a support, a detachable frame suspended from the support and mounted to oscillate therein, a seat suspended from the frame, a back hinged to the frame and seat, a foot rest hinged to the seat and engaging the frame, a covering 55 over said back, seat, and foot rest, said foot rest and back being foldable on to the seat, said suspension frame being foldable along side the seat when detached from the support, said seat, back and foot rest having 60 collapsible, transverse members whereby the

seat, back, and foot rest can be collapsed longitudinally.

6. In a comfort chair, a support, a swinging frame suspended from the support, a chair-back pivotally attached to the frame, 70 a seat, links connecting the rear of the seat to the back below the frame, links connecting the front end of the seat to the frame, a foot rest pivotally connected to the front end of the seat and engaging the links thereat, locking means on the seat for engaging the foot rest when the same is brought to a level therewith, and means for locking the back to the frame at any desired point of the swinging arc of the back, said link connecting the back to the seat having means for locking it to the back when the back is 75 swung downwardly.

7. In a comfort chair, a support, a frame suspended in the support to swing therein, 85 a back pivotally attached to the rear of the frame, a seat, links connecting the rear of the seat to the back below its pivotal connection with the frame, said back and links adapted to interlock when said back is 90 swung downwardly, links connecting the front of the seat to the front of the frame, a foot rest pivotally connected to the front of the seat and engaging the links thereat, locking means in the seat for engaging the 95 foot rest when the same is brought to a level with the seat, means for maintaining said locking means in operative or in inoperative position, an arcuate member carried by the back adjacent the connection of the 100 back with the frame, and means carried by the frame for clamping said arcuate member thereto.

8. In a comfort chair, a support, a frame mounted to oscillate in the support, a back 105 pivotally connected to the frame, a seat suspended from the frame and back, a link centrally pivoted at each side of the front of the frame and having means for engaging the suspension of the seat from the frame, 110 and a foot rest pivotally connected to the links so that a downward displacement of the foot rest causes the links to participate in the movement thereof but not in the upward swinging movement of the foot rest. 115

9. In a comfort chair, a support, triangular frames suspended in the support at one of their apexes, the bases of said frames being in pivotal connection with the sides thereof, a back pivotally connected to the 120 frame, a seat, links connecting the seat to the bases of the frames and to the back, links pivotally connected to the seat at each side in front thereof, a foot rest pivotally connected to said links, locking means between 125 the back and the links connecting the back to the seat, becoming operative when the back is swung downwardly, said links connected to the foot rest having means engageable by the links connecting the base to the 130

seat when the back is swinging downwardly and locking means between the foot rest and the links connected thereto becoming operative when said links are moved by the dis-
5 placement of the back, means for locking said links associated with the foot rest and the seat, and means for locking the back to the bases at any desired position.

10. In a comfort chair, a support having
10 a pair of uprights each comprising a central standard formed of two hinged portions, means normally locking said portions together, a transverse brace pivotally connected to the central standard above the locking
15 means, side members connecting the upper end of the standard to the transverse brace so that the same can be folded over the lower part of the standard, lower transverse brace members, a link pivotally connecting the
20 lower brace members to the lower end of the central standard, side brace members pivotally connecting the lower braces to the first-mentioned transverse brace, a pair of pivotally connected members in pivotal connection
25 with the central standards adjacent the links, a link connecting each of said pivotal members to the upper portion of the adjacent central standard, a pair of pivotally connected members in pivotal connection
30 with the first-mentioned pivotal members, and locking means associated with said second-mentioned pivotally connected members whereby said pairs of pivotally connected members are prevented from moving
35 on their common pivots.

11. In a comfort chair, a seat, a swinging back and a swinging foot rest associated with the seat, said seat, back, and foot rest having side bars, a rod spaced from each bar
40 and secured thereto, a flexible member secured to the rods of the back, seat and foot rest, a transverse member pivotally connected to the side bars of the seat at the top thereof and engaging the flexible member, a
45 transverse member pivotally connected to the side bars of the foot rest at the lower end thereof and also engaging the flexible member, and locking means for maintaining said transverse members at the ends of
50 the side bars whereby the flexible member is maintained taut longitudinally.

12. In a comfort chair, a seat, a swinging back and a swinging foot rest associated with the seat and foldable thereover, said
55 seat, back and foot rest comprising side bars each having a rod spaced therefrom and secured thereto, a flexible member secured to the rods of the back, seat and foot rest, collapsible members, including locking means,
60 connecting the side bars of the seat, said collapsible members being depressed below the flexible member connected to the side bars so that the body of a person occupying the seat cannot come in contact with said
65 collapsible members, a collapsible member

pivots connected to the upper ends of the side bars of the back and adapted to engage one end of the flexible member, locking means for maintaining the flexible member at the ends of the side bars and in engagement with the end of the flexible member, a collapsible member pivotally connected to the side bars of the foot rest at the lower end and adapted to engage the other end of the flexible member, and a collapsible foot bar pivotally connected to the side bars of the foot rest adjacent the collapsible member, said foot bar having means for engaging said collapsible member whereby the same is locked to the end of the side bars of the foot rest and maintained in engagement with the end of the flexible member.

13. In a comfort chair, a seat, a back folding over the seat, a foot rest folding on the seat, and collapsible means associated with said seat, back and foot rest for collapsing the same longitudinally.

14. In a comfort chair, a support, a seat mounted to swing in the support, a pawl in the support, means within the support for locking said pawl in operative or in inoperative position, and a depressible member associated with the seat and adapted to be engaged by the pawl when the same is locked in operative position, whereby the seat is locked to the support.

15. In a comfort chair, a support comprising a pair of uprights each adapted to fold transversely and longitudinally, and means connecting the longitudinally and transversely foldable parts of the upright, whereby the upright is caused to fold longitudinally as the transversely foldable parts of the upright are folded.

16. In a comfort chair, a support comprising a pair of uprights, each having longitudinally and transversely foldable parts, means connecting the longitudinally and transversely foldable parts so as to cause the operation of the longitudinally foldable parts when the transversely foldable parts of the upright are operated, and a collapsible, transverse member uniting the uprights of the support whereby the two uprights may be brought into close proximity.

17. In a comfort chair, a support comprising a pair of uprights each having an upper section mounted to fold over the lower section, said upper section having an extension into the lower section, said lower section having a foldable bottom brace and foldable side members, means pivotally connected to the extension and to the foldable brace whereby when the upper section of the upright is folded over the lower section, the foldable bottom brace is drawn between the side members of the lower section, causing the side members to fall toward each other, and collapsible and transverse members pivotally connected to the extensions of the

upper sections and to the means connecting the extensions to the brace.

18. In a comfort chair, a support comprising a pair of uprights each having a lower section and an upper section foldable over the lower section, said upper section having an extension into the lower section, said lower section having bottom brace members foldable in the plane of the lower section, and side members foldable in the plane of the lower section and associated with the brace members, means pivotally connected to the extension and to the brace members, and collapsible transverse members, including locking means, in pivotal connection with the extensions of the upper section and with the means connecting the extensions to the brace members.
19. In a comfort chair, a support having a pair of uprights each comprising a central standard formed of two portions pivotally connected, a transverse brace connected pivotally to the central standard above the pivot of the standard portions, said members at the upper portion of the standard being connected pivotally to the transverse brace,

lower transverse members, a link connecting pivotally the lower brace members to the end of the lower standard portion, side members connected pivotally to the lower brace members and to the first-mentioned brace, and collapsible, transverse members, including locking means, connected pivotally to the upper standard portion and to the lower standard portion.

35

20. In a comfort chair, a support comprising a pair of uprights each having a lower section and an upper section foldable over the lower section, said lower section having bottom brace members and side members foldable in the plane of the lower section, and means for folding or unfolding said brace and side members operable by the folding movement of the upper section.
